Primary Examiner—Ian Simmons

(74) Attorney, Agent, or Firm—Anthony D. Sabatelli; Melvin Winokur

(57) **CLAIM**

The ornamental design for a pharmaceutical kit, as shown and described.

DESCRIPTION

FIG. 1 is an exploded perspective view, on a reduced scale, of a pharmaceutical kit showing our new design in the fully unfolded position with an uninjected insert card; FIG. 2 is a full scale front plan view thereof; FIG. 3 is a full scale end elevational view thereof; FIG. 4 is a full scale rear plan view thereof; FIG. 5 is a full scale right end elevational view thereof; FIG. 6 is a full scale left end elevational view thereof; FIG. 7 is a full scale front plan view of the insert card of the pharmaceutical kit shown in FIG. 1; FIG. 8 is a full scale rear plan view of the insert card of the pharmaceutical kit shown in FIG. 1; FIG. 9 is a full scale side elevational view of the insert card of the pharmaceutical kit shown in FIG. 1; FIG. 10 is a full scale end elevational view of the insert card of the pharmaceutical kit shown in FIG. 1; FIG. 11 is a full scale perspective view of the pharmaceutical kit shown in FIG. 1 in the fully folded position; and, FIG. 12 is an exploded perspective view, on a reduced scale, in the fully unfolded position with a partially injected insert card.
